SOUNDPROOF WALL

Erwin Meyer, Berlin-Charlottenburg, Germany

Application May 20, 1937, Serial No. 143,837
In Germany July 27, 1935

3 Claims. (Cl. 20—4)

An application was filed in Germany July 27, 1935.

This invention relates to the subject of sound absorption and more particularly to the construction of sound-proof walls for buildings, ships and airplanes.

A primary object of the invention is to provide sound-proof walls constructed in accordance with a given formula certain factors of which 10 may be varied as the circumstances require. In that connection the invention contemplates the sound-proofing of walls by absorbing sound frequencies within a calculated range by analogy to the control of electrical frequencies used in space 15 transmission.

The invention is illustrated in the accompanying drawing, in which:

Figures 1-4, inclusive, are diagrammatic sectional views illustrating the several phases of the 20 invention.

Similar reference characters designate corresponding parts throughout the several views.

Before proceeding to a description to a theory 25 of the invention it may be pointed out that Figure 1 shows a double wall wherein sound absorbing materials are provided in the hollow space adjacent the edges.

Figure 2 shows a double wall unit wherein the sound absorbing materials are arranged in the 30 middle of the space formed between the wall.

Figure 3 illustrates a double wall wherein the interior hollow space is sub-divided by transverse walls or baffles.

Figure 4 illustrates a modification of the 35 invention wherein three spaced walls are utilized together with sound absorbing materials internally arranged along the edges in accordance with the teaching of Fig. 1.

In each of the figures above referred to the 40 masonry or iron beams or girders of the building is indicated as 1, while 2 designates walls or shells consisting of masonry, concrete or any suitable building material. The sound absorbing material such as glass wool, slag wool, felt or the like is designated as 3.

In Figure 3 where interior transverse walls or baffles 4 are used the pockets or cells 5 are formed. The members 4 may be fiber plates, metal plates or the like.

50 In all of the figures the character 1 indicates the width or depth of the air gap.

It is known and has been proved by numerous scientific investigations that the sound transmission of a simple wall substantially depends 55 upon the mass of the latter. According to this

knowledge, considerable sound insulation is only attained by heavy walls. Furthermore, it is known that multiple walls, that is to say, walls consisting of a plurality of individual shells with air spacing afford somewhat more favourable conditions. Heretofore, no particulars have been available regarding their optimum dimensions and also regarding the nature of the air gap. This knowledge gained from numerous tests forms the basis of the present invention. Information regarding the optimum dimensioning of multiple walls may be derived from the similarity with electrical filter circuits. The individual shells act like masses and the air-gaps like springs, that is to say, the individual shells correspond electrically to the inductances and the air gaps to the capacities. Low pass filters transmit low-frequency alternating currents without any considerable attenuation, while on the contrary they attenuate very considerably alternating currents having a frequency beyond a certain frequency, the so-called cut-off frequency. If m signifies the mass of the wall per square centimeter and l the magnitude of the air gap (distance between two walls), then applying this knowledge according to the invention for sound-insulating walls, the value

$$n = \frac{c}{\pi} \sqrt{\frac{\rho}{l \cdot m}}$$

is obtained for the cut-off frequency in cycles per second for sound vibrations passing through the wall. Applicant is the first to disclose this formula, whose validity he has established by comprehensive series of experiments. The form of this equation is suggested by the analogy of known relations of frequency, inductance, and capacity in an electrical low pass filter, but experimental work was necessary to establish its validity in acoustic phenomena in walls. In this 40 formula ρ signifies the air density in grams per cubic centimeter and c the velocity of sound in centimeters per second. The cut-off frequency is therefore lower, the greater the mass of an individual shell and the greater the air spacing. 45 The sound absorption or the impenetrability to sound of a wall must be of equal magnitude for all occurring pitches of sound. For the multiple wall, the dimensioning rule may therefore be expressed by stating that the individual shell mass and the air spacing should be selected so that the cut-off frequency is lower than the practically occurring and disturbing pitches of sound. For example, a cut-off frequency of 100 cycles 50 should suffice for many purposes; in other cases 55

in which the source of disturbance is of a higher frequency, a higher cut-off frequency in itself will suffice. Its position also depends upon whether the sound process on the other side of the wall cannot be heard at all or, like speech, can merely no longer be understood. Experiments have shown that for a simple wall with two shells, for the most widely differing combinations of wall shell mass and air gap magnitude, the value given by the above formula for the cut off frequency agrees excellently with observed values. On the other hand, in a multiple wall consisting of three or more shells and a series of wall masses and air cushions, a substantially smaller attenuation is observed than would be expected according to formulas based on the electrical analogy.

The multiple wall has a salient cut off frequency which is imparted to it by the mass of the wall and the length of the air cushion. The transmission velocity through the multiple wall for particular individual frequencies is found to decrease as the pitch of the impinging sound approaches the cut-off frequency. While the velocity of sound may be considered to be the same for all frequencies for a homogeneous wall, this condition does not obtain for a non-homogeneous laminated wall consisting of stacked layers of different media. These relations also are along the lines of the analogous electrical filter.

The smaller value of attenuation for the multiple wall particularly in the neighborhood of the cut-off frequency, than would be expected from the electrical analogy, may be explained by considering the fact that while the distance between adjacent shells of the multiple wall, considered up to even high frequencies, is generally less than the wave length, but on the other hand the dimension of the air cushion parallel to the surface of the shells is on the contrary not small with reference to the wave length of the impinging sound. It has been found that transverse vibrations or oscillations and hence resonance effects are caused in these air cushions parallel to the surface of the shells, and these oscillations diminish the sound insulation.

The second feature of the present invention, therefore, resides in interrupting or preventing such oscillations and resonance effects by interrupting the spread of sound in directions parallel to the shell surfaces, or by using sound absorbing materials in the air chamber. In this manner, these oscillations and resonance effects can be eliminated, and attenuation or damping effects can be produced which rise sharply with the frequency. For example, it has been found that a multiple wall built along the lines here described and having a wall weight of 50 kilograms per square meter, has a transmission loss of 55 decibels, that is, it corresponds to a solid brick wall 50 centimeters thick and weighing 1000 kilograms per square meter. This interruption may be effected in various ways, for example by the insertion of light or porous materials, or by subdividing the air cushion by means of lattice work in such a manner that the newly formed spaces, in respect of their dimensions parallel to the wall surface, are small in comparison with the wave length. In some cases, it is merely necessary, according to the invention, to apply the porous sound-absorbing substances or materials only at the edges of the air cushion. The resonance of the transverse oscillations of the air cushion is likewise prevented thereby, and hence the sound absorption is considerably increased.

With the said means, the sound attenuation is increased particularly beyond the cut-off frequency, that is to say from the cut-off frequency towards the higher tones. In order also to diminish the transmission of sound below the cut-off frequency—this being the third feature of the new wall combination—it is necessary, in the same way as in the case of electric filters, to introduce a "reflection damping factor" in the transmission between the individual elements of the multiple wall. This is effected as follows: The cut-off frequency is a function of the product of the wall mass and depth or length of the air cushion and more specifically varies inversely with the square root of the product of wall mass and depth of air cushion, in accordance with the formula above given. The acoustic impedance of the system is a function of the quotient of unit wall mass m divided by the depth l of the space between adjacent shells or walls, and is given by the equation

$$Z = c \sqrt{\frac{\rho m}{l}}$$

where ρ is the density of air in grams per cubic centimeter and c is the sound velocity in centimeters per second. This formula has been empirically derived by applicant by a study of his own extended experimental observations, and its form is suggested by the analogy of the corresponding electrical filter relations. For the purposes of the present application, the essential feature is that the acoustic impedance is a function of the quotient of unit mass divided by air space depth, while the cut-off frequency is a function of the product of these same quantities. In order to diminish the transmission of sound in the frequency range of transmission, the above-mentioned quotient is selectively varied in such manner as appears desirable for the several individual sections of the multiple wall, while the product of these quantities of wall mass and air cushion depth is kept substantially constant. Additional attenuation is thereby introduced between the individual members of the multiple wall. The sound is reflected at the point concerned, whereby the sound attenuation is increased. Of course the last means is only possible with walls having three or more shells, while the earlier consideration relates also to walls with two shells. The materials from which the wall is made are without significance, the magnitude of their mass alone being important. Practical tests have shown that by applying the means described herein, walls may be made having a sound transmission less than that of a solid brick wall of the same thickness and 20 times heavier. A necessary condition for securing a high transmission loss to sound is of course the prevention of solid sound bridges between the individual walls. If solid connections between the walls are necessary for static reasons, solid sound-absorbing materials (cork, felt, rubber and so forth) or springs or both should be inserted at those places for isolating the sound.

I claim:

1. In a multiple-layer sound-proof wall to transmit substantially no sound vibrations of frequencies exceeding a predetermined cut-off frequency n cycles per second, a plurality of substantially parallel shells respectively of different masses per square centimeter of shell surface, $m_1, m_2, m_3, \dots$ and respectively spaced apart by air gaps of different lengths in centimeters, $l_1, l_2, l_3, \dots$, said pairs of values of mass and

length being so selected that the products m_1l_1 , m_2l_2 , m_3l_3 remain substantially equal to each other while the quotients

$$\frac{m_1}{l_1}, \frac{m_2}{l_2}, \frac{m_3}{l_3}, \dots$$

5 vary over a considerable range, said values of length, l_1 , l_2 , l_3 being respectively determined for the corresponding masses m_1 , m_2 , m_3 , $\dots$ by the form of equation

10

$$l = \frac{c^2 \rho}{\pi^2 n^2 m}$$

where c is the velocity of sound in air in centi-

meters per second and ρ is the density of air in grams per cubic centimeter.

2. A wall as set forth in claim 1, including a lattice structure in each of said gaps formed of interlaced strips substantially perpendicular to the faces of said shells.

3. A wall as set forth in claim 1, including a lattice structure in each of said gaps formed of interlaced strips substantially perpendicular to the faces of said shells and separated from each other by spaces which are small in comparison with the cut-off wave length.
